HAND CRUTCH

Ludwig E. Lundquist, Brooklyn, N. Y.

Application December 16, 1938, Serial No. 246,091

13 Claims. (Cl. 135—49)

The present invention relates to an improvement in hand crutches and is especially adapted for use in sick rooms or hospitals and the like, and is designed to be an aid to convalescents, especially those who have been bedridden for an extended period of time. The present crutch, though it may be otherwise used, performs several functions, first, it enables a convalescing invalid to get out of bed and secondly to move about the room, unassisted, and thirdly to permit the invalid to gradually recover, by exercise, the use of his or her limbs, all of which is accomplished without aid, from others.

One of the main features of the present device is in the formation, whereby the center of gravity and load are offset in such a manner that the foot-piece of the crutch may be set well under a bed and the handles set well over the bed, when the user is in sitting position on the edge of the bed, thus placing the handles of the crutch well under the hands and arms of the user, and near to the center of gravity of the body of the user. This enables the user to rise substantially vertically from the bed, thus enabling the user to use both arms to attain standing position, without leaning forward and thus losing fulcrum and balance, in arising. Thereafter, the user may slide, first one crutch and then the other in operating sequence, keeping his or her weight well balanced by the arms, and supported thereby, and relieving the legs of considerable of the load. Thus, the legs may become gradually accustomed to use, and eventually become normal.

Another feature of advantage is in the light weight of the crutches, thus relieving the user from excess weight and in addition to the other features of advantage render the crutches sanitary, and easily cleaned and sterilized.

The foregoing and other features of advantage will be apprehended as the herein description proceeds and it will be obvious that modifications may be made in the structure herein disclosed, without departing from the spirit hereof or the scope of the appended claims.

In the drawing,

Fig. 1 is a view in side elevation of one form of the present device;

Fig. 2 is a side view of Fig. 1;

Fig. 3 is a bottom view of Fig. 1;

Fig. 4 is an enlarged fragmentary view in section, of the handle;

Fig. 5 is a transverse sectional view taken on line 5—5, Fig. 4, looking in the direction of the arrows;

Fig. 6 is an enlarged, fragmentary view of

another form of handle construction, in partial transverse section;

Fig. 7 is an enlarged, fragmentary view of a tubular end engaging flanged section in perspective;

Fig. 8 is a fragmented side view of the modified structure shown in Fig. 9;

Fig. 9 is a plan view partially sectioned of a modified form of crutch foot; and

Fig. 10 is a side view in any elevation, in a reduced scale in a modified form of crutch.

The device, generally denoted by 1, is used in pairs, like crutches and comprise a foot portion 2, made of metal tubing, for lightness and strength, is made of one piece, formed into a rectangular construction the ends of which are joined together at 12, Figs. 1 and 3, the foot being elongate one way and narrow the other way.

The joined end of 2 is welded or brazed to the lower flanged end of an inclined straight strut tube 3, said strut being inclined to the left, as viewed in Fig. 1. The lower flanged end 9 of the tube 3, is flanged in a so-called fish-mouth joint, which embraces the diameter of the foot tube on both sides of the joint 12, and when thus affixed firmly binds the flanged tube joint 9 about the joint 12, and thus fixes this joint firmly together in integral assembly.

The upper end of strut 3 is flattened, Figs. 1 and 4, as at 5, the outer end of said flattened portion being rounded as at 16, Fig. 2 and this flattened rounded end is set into a recess in the metal handle forming tube 14, Fig. 4. The handle tube 14, at its opposite ends, is closed by two plugs 15—15, which may be firmly affixed in recessed position by brazing. Before assembly of the support or strut tubes 3 and 4 to the handle structure a rubber grip 13 may be drawn over the tube 14, and then the support tubes 3 and 4, properly flattened at their ends 5 and 6, may be riveted to the handle tube, by a rivet 7, which passes through tube 14 and is headed as at 8, Fig. 4, over the flattened ends 5 and 6.

A modified form of handle is shown in Fig. 6, wherein a handle forming tube is dispensed with, the tube ends 3' and 4' being bent at the proper angles and joined at the mid point 17. An inner metal tube 13 is telescopically mounted in the interior of tube ends 3' and 4', to stiffen them, and a rubber handle forming tube H is mounted upon the tube ends 3' and 4' to form a grip.

As shown in Fig. 1, the strut supporting tube 4, is curved inwardly until it contacts at about its mid-point with approximately the mid-point

of tube 3, and then, curving outwardly is attached by its flanged lower end 10, by brazing or otherwise, Fig. 7, to the foot tube 2 at a point opposite the point of attachment of tube 3 to the foot piece 2. Thus, the foot piece is connected to the strut tubes 3 and 4 with its elongate length between said strut tubes, as shown in Fig. 3. The tubes 3 and 4, at their mid-contacting points may be riveted, as at 11, Fig. 1, or otherwise suitably joined at this point, for rigidifying the support structure. This curvature of the strut 4, permits, as illustrated in Fig. 1, of the foot portion 2 and the grip portion H to pass under and over the bed edge and thus bring the crutch support close to the user, while seated on the bed edge.

A modified form of foot piece and mode of strut tube attachment is shown in Figs. 8 and 9, wherein the foot piece 2' is made of an elongate wooden piece 2', upon which is attached the lower extremities 19 and 20 of the coacting strut pieces 3 and 4 respectively. To this end the lower ends of the strut pieces are flattened, as in Figs. 8 and 10, at 19 and 20, and the flattened ends are then curved or bent, as shown in Fig. 8, so that the flattened ends lie in a parallel plane to the surface of base 2', and are then affixed to said base by screws 21. This structure is rigid and satisfactory, and is an economical way to construct the base end of this device, and maintain lightness, strength and sanitary conditions.

A further modified form of crutch is shown in Fig. 10, wherein the crutch includes a hand crutch portion generally denoted by 1, but the handle portion is so modified that the inclined strut portion 3'' is provided with bushing 1, the upper open end, the bushing being provided with a threaded thumb nut T, and a telescopic extension tube R is slidably mounted to reciprocate within the strut 3''. The upper part of the telescopic tube R is provided with an offset grip portion 13, which forms a grip H' which is affixed to the tube R, by means of a through rivet 8.

When the tube R is fully telescoped downwardly, the handle H' rests in contact with the handle H, and this double grip then forms a single grip for hand crutch purposes.

When the tube R is arranged in the position shown in Fig. 10, and is locked in said position by the thumb nut T, the crutch becomes in effect a hand crutch and a shoulder crutch, so that the user may first utilize the hand crutch to arise from sitting position, and after having arisen, to use the crutch as a shoulder crutch.

Having thus described the invention what is claimed is:

1. A hand crutch comprising an elongate, rectangular, tubular base portion, a tubular hand grip portion remote from said base portion and in parallel relation thereto, said base and grip portions being relatively offset from one another longitudinally, an upright, inclined tubular strut joining corresponding ends of said base and grip portions, a second upright strut joining the opposite ends of said base and grip portions, said latter upright being incurved and contacting with the mid-portion of said first strut and means for affixing said struts together at said contact point.

2. A hand crutch as set forth in claim 1, in which the hand grip portion is formed of a tubular base, heads set in the ends of said tube

to form a recessed closure at each end, the upper ends of said struts having flat faces and rounded edges, said ends being mounted in said recesses, means for fastening said ends in said recesses and an outer tubular rubber grip portion mounted upon the exterior of said tubular base.

3. A hand crutch as described in claim 1, wherein the hand grip portion comprises end portions of the said struts which are bent at angles and contact with each other, a plug fitted in said bent tubular ends and a rubber hand grip portion mounted upon the exterior of said bent tubular ends.

4. A hand crutch comprising an elongate base, a hand grip portion remote from said base and located in parallel relation to said base, said base and grip portions being relatively offset longitudinally from each other, and a pair of upright, longitudinally inclined struts affixed to said grip and base portions to fixedly hold said base and grip portions in said offset positions.

5. A hand crutch comprising an elongate base, a hand crutch portion remote from said base and located in parallel relation to said base, a pair of substantially upright struts joining said crutch and base portion and a telescopic grip portion mounted for slidable movement in one of said strut portions.

6. A hand crutch comprising an elongate base, a hand crutch portion remote from said base and located in parallel relation to said base, a pair of upright struts joining said crutch and base portion and a telescopic portion mounted for slidable movement in one of said strut portions and means for locking said slidable strut portion in any adjusted position.

7. A crutch comprising a base having a part adapted to rest on a floor; a grip; supporting means supporting said grip on and above said part; all of the structure of said supporting means at a predetermined height being entirely forward of a perpendicular passing through the rear end of the grip and said part while the part is resting on the floor.

8. A crutch comprising a part having a point adapted to rest on a floor; a grip; supporting means supporting said grip above said part; all structure of said supporting means at a predetermined height being entirely forward of a perpendicular passing through said point and the portion of the grip to the rear of its center while said point is on the floor.

9. A crutch comprising a base having separated parts adapted to rest simultaneously on a floor; a grip; supporting means supporting said grips above and on the base; all of the structure of said supporting means at a predetermined height being entirely forward of perpendiculars passing through the grips and between said parts.

10. A crutch comprising a base having front and rear parts adapted to rest simultaneously on a floor; a grip; supporting means supporting said grip on and above the base; all of the structure of said supporting means at a predetermined height being entirely forward of a perpendicular passing between said parts and through the grip.

11. A crutch comprising a base having front and rear parts adapted to rest simultaneously on a floor; a grip; supporting means supporting said grip on the base; all structure of said means at a predetermined height being forward of perpendiculars passing through the forward part and the forward end of the grip.

12. A crutch comprising a wide elongated base adapted to rest flat on a floor; a grip; supporting

means supporting said grip above the space within the effective perimeter of the base, whereby said grip is supported in stable equilibrium; all of the structure of said supporting means at bed height being entirely forward of perpendiculars passing through the forward ends of the grip.

5 13. A crutch comprising a wide elongated base adapted to rest flat on a floor; upper and lower

grips; supporting means supporting said grips above the space within the effective perimeter of the base, whereby said grips are supported in stable equilibrium; all of the portion of said supporting means at bed height being entirely forward of perpendiculars passing through the forward ends of the grips.
